UNITED STATES PATENT OFFICE.

CLAUD E. FULLER, OF KANSAS CITY, MISSOURI.

APPARATUS FOR TREATING POROUS BLOCKS.

1,247,105.

Specification of Letters Patent. Patented Nov. 20, 1917.

Application filed October 9, 1915. Serial No. 55,064.

To all whom it may concern:

Be it known that I, CLAUD E. FULLER, a citizen of the United States, residing at Kansas City, in the county of Jackson and 5 State of Missouri, have invented a certain new and useful Improvement in Apparatus for Treating Porous Blocks, of which the following is a specification.

My invention relates to improvements in 10 apparatus for treating porous blocks.

It relates to the treating of porous paving blocks, such as bricks, consisting in filling the pores of the blocks with material, such as liquid bitumen, preferably in the 15 form of asphalt, whereby the blocks will be rendered very durable and impervious to moisture, will have their resiliency increased, and, when used for street paving, will be comparatively noiseless under traffic. 20 conditions.

In Letters Patent Numbers 1,063,964 and 1,063,965, issued to me June 10, 1913, there are described a method and apparatus for treating paving blocks, in which the blocks 25 are first heated, after which the air is exhausted therefrom, following which the blocks are immersed in liquid bitumen, the blocks being held under pressure greater than atmospheric during such immersion, 30 after which the immersing fluid is withdrawn from the immersing chamber and the blocks permitted to cool, while still under pressure, until the bitumen contained in the blocks has solidified. The cooling of the 35 blocks while held in the immersion chamber under pressure consumes an extended period of time, during which the treatment of other blocks in the same chamber cannot be proceeded with. The treatment under such 40 process and with such apparatus is, therefore, expensive and the production is greatly limited. If the blocks are removed from the immersion chamber to permit of the use of the chamber for the immersion of other 45 blocks, and the blocks which have been immersed are left in the open air, the asphalt coating on the exterior of the blocks will

quickly cool and solidify and the blocks will be stuck together in a solid mass.

The object of my present invention is to 50 provide a novel and improved apparatus by which the cost of treatment will be greatly decreased and by which the output will be largely increased.

In my present invention, the blocks or 55 bricks, after immersion in the liquid bitumen, are gradually cooled in a temperature below the melting point of the bitumen and above the ordinary atmospheric temperature and at substantially atmospheric pressure. 60

As the blocks are gradually cooled, the outer coating of bitumen will be absorbed 65 into the pores of the blocks as the bitumen contracts in cooling, due to the fact that the coefficient of expansion of the bitumen is greater than that of the blocks or bricks, and due to the fact that the exterior coating of bitumen is retained at a temperature sufficiently high to prevent its solidification 70 until it has been absorbed into the pores of the blocks.

Blocks treated with my present apparatus will, when cooled, not stick together, and the output will be largely increased due to the fact that, after one set of blocks has 75 been immersed, another set may be immersed without delay. For the purpose of gradually cooling the blocks, I provide protective means, comprising preferably a closed cooling chamber, having provision for preventing cooling to solidification of the surface liquid on the blocks until it has been absorbed by the blocks. 80

In the accompanying drawings, which illustrate the preferred embodiment of my 85 invention,

Figure 1 is a longitudinal view partly in vertical section and partly in elevation of the immersing chamber, the tank for containing the liquid filling material, and parts 90 connected therewith.

Fig. 2 is an enlarged vertical section on the line 2-2 of Fig. 1, the car loaded with blocks being omitted.

Fig. 3 is an enlarged vertical section on the line 3—3 of Fig. 1.

Fig. 4 is a reduced horizontal sectional view of the immersing, pre-heating and cooling chambers and parts connected therewith.

Fig. 5 is an enlarged cross section on the line 5—5 of Fig. 4.

Fig. 6 is a vertical sectional view on the line 6—6 of Fig. 5.

Similar reference characters designate similar parts in the different views.

The chamber in which the blocks are immersed comprises a horizontal metal cylinder 1 having its inner end closed and provided at its outer end with a swinging door 2, which is preferably hinged at its upper edge and is adapted to be swung upwardly to the open position by means of a suitable block and tackle 3, Fig. 1. The door 2 is provided with suitable clamping devices 4 for holding it tightly closed during the immersing operation. A track 5 extends longitudinally into the immersing cylinder 1 and is provided with two branches 6 and 7, which extend respectively into a preheating chamber 8 and a cooling or tempering chamber 9, Fig. 4.

The blocks 10 to be treated are mounted upon cars, one of which, designated by 11, is shown in the immersing cylinder 1, mounted on the track 5. Doors 12 and 13 are provided for closing the ends respectively of the pre-heating chamber 8. Doors 14 and 15 are provided for respectively closing the ends of the cooling chamber 9.

The immersing cylinder 1 is mounted in a furnace 16, which is provided in its lower portion with a horizontal longitudinal flue 17, which discharges upwardly between a plurality of parallel horizontal transverse baffling members 18 and against the under side of the cylinder 1.

Mounted in the furnace 16 above the immersing cylinder 1 is a supply tank 19 which is adapted to contain the supply of bituminous material with which the blocks 10 are to be impregnated. The tank 19 is supported upon transverse bars 20, the ends of which are supported by the walls of the furnace 16, and the middle portions of which may be supported by pillars 21, mounted on the cylinder 1.

Horizontal shelves 22 extend longitudinally along the walls of the furnace 16 at opposite sides of and against the cylinder 1 from the rear end of the furnace to a point adjacent to the forward end of the cylinder 1.

Shelves 23 extend longitudinally along the walls of the furnace 16 at opposite sides of and against the tank 19 from the forward end of the furnace to a point adjacent to the rear end thereof.

A burner 24 discharges into the rear end of the flue 17. The products of combustion from said burner pass forwardly through the flue 17, thence upwardly between the baffling members 18, thence forwardly to and around the forward ends of the shelves 22, thence upwardly and rearwardly over 70 said shelves and against the tank 19, thence rearwardly to and around the rear ends of the shelves 23, and thence forwardly above said shelves, into the smoke stack 25 with which the furnace 16 is provided.

For supplementing the heat from the burner 24, burners 26 may be provided. These burners are arranged to discharge rearwardly between the cylinder 1 and the tank 19 at the forward end of the furnace 16.

For heating the tank 19 interiorly, there are placed therein a plurality of steam pipe coils 27, one set of ends of which connect with a header 28, and the other set of ends of which connect with a header 29. The headers 28 and 29 and the coils 27 form a steamer radiator, which is supplied with steam by a steam pipe 30, which connects with the header 28 and with the boiler of a steam producer 31, which, preferably, discharges its gaseous products of combustion into the furnace 16 through a pipe 32. A pipe 33 is connected to the header 29 and to the boiler of the steam producer 31.

For ascertaining the temperature of the interior of the cylinder 1, it may have extending from the outside into it thermometers 34 disposed at suitable places. Thermometers 35 are similarly provided for the tank 19.

The baffling members 18 are preferably adjustable toward and from each other, those farthest from the burner 24 being spaced farther apart than those nearer to said burner.

For transferring the liquid bitumen from the tank 19 to the immersing cylinder 1, and for returning the bitumen to the tank 19, a conductor 36 is connected to the lower side of the cylinder 1 and is provided with two branches 37 and 38 which are respectively connected to the lower side and the upper side of the tank 19. Shut-off valves 39 and 40 are respectively located in the branches 37 and 38.

Adjacent to the immersing cylinder 1 is an air pump 41 of any suitable type. Means are provided by which the pump 41 may exhaust air from the cylinder 1 or force air into said cylinder, as may be desired. For effecting these functions I have provided the following described mechanism:

The pump 41 is provided with a cylinder 42 in which is mounted a reciprocative piston 43. A conductor 44 is connected to the upper side of the cylinder 1, and is provided

with two branches 45 and 46 connected to the cylinder 42 adjacent to the respective ends thereof. In the branch 45 are located a shut-off valve 47 and a check valve 48. In 5 the branch 46 are located a shut-off valve 49 and a check valve 50. The branch 45 is provided with a branch 51 open to the atmosphere and provided with a shut-off valve 52 and a check valve 53. The branch 46 is 10 provided with a branch 54 open to the atmosphere and having a shut-off valve 55 and a check valve 56. The check valves 48 and 56 open toward the cylinder 42, and the valves 49 and 53 open away from the cylinder 42. 15

Connected to the cylinder 42 adjacent to its respective ends are exhaust pipes 57 and 58 in which are respectively located shut-off valves 59 and 60.

20 When it is desired to exhaust the air from the cylinder 1, the door 2 is closed as are the valves 39 and 40. The valves 47, 52 and 60 are opened, and the valves 49, 55 and 59 are closed. The piston 43 is then reciprocated 25 upon which air will be drawn from the cylinder 1 through the conductor 44 and branch 45 into the pump cylinder 42 and then discharged to the atmosphere through the branch 45 and branch 51.

30 In pumping air into the cylinder 1, the valves 39, 40, 47, 52 and 60 are closed and the valves 49, 55 and 59 are opened. When the piston 43 is reciprocated, air will be drawn into the pump cylinder 42 through 35 the branches 46 and 54 and discharged into the cylinder 1 through the branch 46 and conductor 44.

Connected to the conductor 44 may be provided a pressure gage 61 and a vacuum 40 gage 62 by which the air pressure in the cylinder 1 may be determined.

For the purpose of determining the level of the immersing liquid in the immersing cylinder 1, there may be provided a float 63 45 having a vertical upwardly extending stem 64 vertically movable in the conductor 44 and adapted to enter the transparent extension 65 with which the conductor 44 is provided.

50 Below the chambers 8 and 9 respectively are two longitudinal flues 67 and 66 respectively, which respectively discharge upwardly between baffling members 68, corresponding to the baffling members 18, into 55 the pre-heating chamber 8 and cooling chamber 9.

Discharging respectively into one set of ends of the flues 67 and 66 are burners 69 and 70.

60 A discharge conductor 71 having rotatably mounted in it an exhaust fan 72 has two branches 73 and 74 which respectively connect to the upper parts and right hand

ends, as viewed in Fig. 6 and Fig. 4 of the chambers 8 and 9. In the branches 73 and 74 65 are respectively mounted two swinging dampers 75 and 76, which respectively control the amount of air drawn from the chambers 8 and 9 by the exhaust fan 72. By proper control of the burners 69 and 70 and 70 of the dampers 75 and 76, temperatures respectively suitable for the purposes of the pre-heating chamber 8 and cooling chamber 9 may be provided.

The track 5, where it enters the immersing 75 chamber 1, is provided with two removable rail sections, Fig. 4, which may be removed to permit of the closing and opening of the door 2.

In the operation of my invention, the 80 door 12 is opened and cars, corresponding to the car 11, loaded with the blocks 10, which are to be treated, are run on the track 6 into the pre-heating chamber 8. This chamber may be retained at a temperature above the 85 melting point of the filling material to be employed in impregnating the blocks. When the blocks are heated to the desired temperature, the doors 13 and 2 are opened, and the cars carrying the blocks are run 90 into the immersing cylinder 1 upon the track 5.

In the meantime, the burner 24 and the steam producer 31 have been operated so as to heat the immersing cylinder 1 to the 95 proper temperature, and to heat the tank 19 sufficiently to melt the filling material which is contained therein. If the filling material is asphalt, the interior of the cylinder 1 and tank 19 will be heated above the 100 melting point of the asphalt, the door 2 having been closed and tightly clamped by means of the securing devices 4, which may be swinging bolts provided with nuts, such as are commonly provided for purposes of 105 this kind.

The pump 41 is then operated, in the manner hereinbefore described, to exhaust the air from the immersing cylinder 1. The shut-off valve 39 is then opened, thereby 110 permitting the melted filling material to flow from the tank 19 through the conductor 36 and its branch 37 into the cylinder 1 until the blocks 10 in said cylinder are 115 immersed. The valve 39 is then closed, and the pump 41 is operated to force air into the immersing cylinder 31. After a sufficient pressure has been produced in the cylinder 1, the valves 47 and 49 are closed, following which the blocks are permitted to 120 remain in the cylinder 1 under pressure and immersed until their pores have been completely filled with the immersing liquid. The valve 40 is then opened and also the valve 49 and valves 55 and 59, and the pump 125 41 is again operated to pump air into the

cylinder 1. The air pressure in said cylinder will force the liquid filling material from the cylinder 1 through the conductor 36 and branch 38 into the tank 19.

5 After the cylinder 1 has been emptied of the liquid filling material, the door 2 is opened, the rail sections 77 put in place and the cars 11 loaded with the impregnated blocks 10 are run over the branch track 7 into the cooling chamber 9, the door 15 thereof being opened for this purpose. After the cars have been run into the cooling chamber, the door 15 is closed, and the blocks are allowed to remain in the cooling chamber until the filling material has solidified. During this period of time, the temperature in the cooling chamber 9 is retained below the melting point of the filling material, and at a point sufficiently high above 20 atmospheric temperature to prevent the sudden cooling of the blocks and the consequent chilling of the impregnating material which covers the exterior of the blocks. As the impregnating material gradually cools, it 25 will, by reason of its coefficient of expansion being greater than that of the blocks, if such blocks are brick or similar material, contract to a greater extent than the blocks, whereby the coating of the impregnating material 30 on the exterior of the blocks will be drawn into the pores of the blocks; so that when the blocks have been cooled sufficiently to solidify the impregnating material contained therein, the blocks will not stick together 35 but may be easily separated after the door 14 has been opened and the cars have been run out of the cooling chamber.

While the cooling operation is being carried on, an instalment of pre-heating blocks 40 may be undergoing immersion in the chamber 1, and another set of blocks may be, at the same time, undergoing the pre-heating operation in the chamber 8. The operation may thus be made practically continuous, 45 thereby effecting a great saving in fuel and time and a large increase in the output of the apparatus.

By reason of the contiguity of the chambers 8 and 9, the heating from the chamber 50 8 may be employed by conduction for assisting in heating the chamber 9.

Various modifications of my invention, within the scope of the appended claims, 55 may be made without departing from its spirit.

What I claim is:—

1. In an apparatus for treating porous blocks, an immersing chamber, a pre-heating chamber, a protective cooling chamber 60 having provision for preventing cooling to solidification of the surface liquid on the blocks until it has been absorbed by the blocks, and means by which the blocks may be transferred from the pre-heating chamber to the immersing chamber and thence to the cooling chamber.
2. In an apparatus for treating paving blocks, an immersing chamber, a pre-heating chamber, a closed cooling chamber, a track connecting said chambers, and a car 70 adapted to carry the blocks to be treated and to run upon said track into said chambers.
3. In an apparatus for treating paving blocks, an immersing chamber, a pre-heating chamber, a closed cooling chamber, a 75 track running into said immersing chamber and having two branches running respectively into said pre-heating and cooling chambers, and a car adapted to carry the blocks to be treated and to run upon said 80 track and into said chambers.
4. In an apparatus for treating paving blocks, an immersing chamber, a pre-heating chamber, a closed cooling chamber, means for independently heating said chambers, and means by which the blocks to be treated may be transferred from one of said chambers to the others.
5. In an apparatus for treating porous blocks, an immersing chamber, a protective 90 cooling chamber having provision for preventing cooling to solidification of the surface liquid on the blocks until it has been absorbed by the blocks, and means by which the blocks may be transferred from the immersing chamber to the cooling chamber.
6. In an apparatus for treating paving blocks, an immersing chamber, a closed cooling chamber having means by which the blocks may be cooled in air at substantially atmospheric pressure and having a temperature above ordinary atmospheric temperature, means for heating said chambers, and means by which the blocks to be treated may be transferred from the immersing chamber to the cooling chamber.
7. In an apparatus for treating paving blocks, a pre-heating chamber, a closed cooling chamber, heating means by which said chambers may be retained at different temperatures and the heat conducted from one to the other, and means by which the blocks to be treated may be transferred from one of said chambers to the other.
8. In an apparatus for treating porous blocks, an immersing chamber for receiving the blocks, means by which blocks held in said chamber may be immersed in a liquid substance which solidifies at ordinary atmospheric temperature, means by which the blocks after such immersion may be transferred from said immersing means, and protective means by which the transferred immersed blocks may be gradually cooled in a temperature below the melting point of said liquid substance and above ordinary at-

mospheric temperature and at substantially atmospheric pressure, said protective means having provision for preventing cooling to solidification of the surface liquid on the blocks until it has been absorbed by the blocks.

9. An apparatus for treating porous blocks, an immersing chamber for receiving the blocks, means by which said blocks held in said chamber may be impregnated with a liquid substance which solidifies at ordinary atmospheric temperature, means for pre-heating the blocks before such impregnation, means by which the blocks after im-

pregnation may be transferred from said 15 impregnating means, and protective means by which the transferred immersed blocks may be gradually cooled at a temperature above ordinary atmospheric temperature and at substantially atmospheric pressure, 20 said protective means having provision for preventing cooling to solidification of the surface liquid on the blocks until it has been absorbed by the blocks.

In testimony whereof I have signed my 25 name to this specification.

CLAUDE E. FULLER.
